UNITED STATES PATENT OFFICE

118,312

DESIGN FOR A DIRECTIONAL SIGNAL CASING

Orson M. Pope, Los Angeles, Calif.

Application October 7, 1939, Serial No. 87,567

Term of patent 14 years

To all whom it may concern:

Be it known that I, Orson M. Pope, a citizen of the United States, residing at Los Angeles, in the county of Los Angeles and State of California, have invented a new, original, and ornamental Design for Directional Signal Casings, of which the following is a specification, reference being had to the accompanying drawing, forming part thereof.

Fig. 1 is a top perspective view of the directional signal casing showing my design.

Fig. 2 is a front view.

Fig. 3 is a side view, and,

Fig. 4 is an end view.

I claim:

The ornamental design for a directional signal casing, as shown.

ORSON M. POPE.
